UNITED STATES PATENT OFFICE

FREDERICK JOHN CHEMIDLIN, OF PLAINFIELD, NEW JERSEY, ASSIGNOR TO BRONSTON HAT CO., INC., OF PLAINFIELD, NEW JERSEY

HATBAND FASTENER

Application filed November 15, 1929. Serial No. 407,408.

This invention relates to improvements in fastening devices for hat bands and particularly to a fastening device which may be instantly attached or detached and which makes it feasible for an inexperienced person to quickly interchange hat bands.

An object of this invention is to provide a hook member to fasten the plain end of the hat band to the crown or body of the hat, the hook member having prongs gripping the hat body in one direction and to provide a fastening device at the bow end of the hat band with hinged prongs gripping the hat body in the opposite direction, and to set up a tension in the hat band to act upon and maintain the opposite prongs in fixed position.

A further object of this invention resides in the provision for hiding the fastening devices from sight, so as not to mar the ornamental appearance of the hat to which the hatband is affixed.

With the above and other objects in view, the invention will be hereinafter more particularly described and the combination and arrangement of parts will be shown in the accompanying drawings, and pointed out in the claims which form part of this specification. It being understood that the embodiment herewith shown, is merely illustrative and that various changes in the form, proportion, size, and minor details of construction within the scope of the claims, may be resorted to without departing from the spirit or sacrificing any of the advantages of the invention.

Reference will now be had to the drawings, wherein like numerals of reference designate corresponding parts throughout the several views, in which:

Figure 1 is a fragmentary perspective view of a hat with the hatband in an open position.

Figure 2 is a fragmentary sectional top view of the hatband and fastening device.

Figure 3 is a perspective view of the fastening device for the bow end.

Figure 4 is a section taken on line 4-4 of Figure 3.

Figure 5 is a development view of a plate for the fastening device.

In the illustrated embodiment of the invention shown, 10 designates the brim and 11 designates the crown of a hat to which is affixed a hatband 12, of the type generally employed in the art.

As is usual in the art, the hatband 12, is provided with a bow 13, having a closed end portion or loop 14. The plain end of the hatband is designated by the numeral 15. The plain end is fastened to the crown by means of a hook member 16 laced through the hatband and having bent prongs 17, 17, which are pressed into, and engage the crown wall of the hat.

Hidden from view within the closed end portion 14, of the bow 13, is the fastening device, best shown in Figure 3. This device designated by the numeral 18, comprises a thin metal plate 19, folded over and having on one side, protruded rib portions 20, 21, and apertures 22, 23, 24. The rib portions are convex and adapted to function as hinge elements in which is placed a wire 25 having two pointed prongs 26, 27 and a central loop portion 28. This pronged wire is thus adapted to rotate relative to the member 19.

When the fastening device 18, is placed in operating position within the bow portion 14, the prongs 26, 27 and the loop 28 pierce the fabric of the bow end of the band, and project out laterally from the reverse side of the bow and lay flat, and point longitudinally away from the end 14, so that when the hatband encircles the crown 11, the prongs 26, 27 point in opposite direction to the end of the prongs 17, 17 of the hook member 16.

When it is desired to attach a hatband equipped with my improved fastening devices, the hook member 16, is laced through the plain end 15 of the hatband, and the prongs 17, 17, are pressed into engaging position with the crown wall of the hat. The bow end of the band is then carried around the crown and drawn up until the hat band encircles the crown and the bow 13 overlaps the plain end 15. The bow end carrying the fastening device 18, is then gripped and pulled up tightly around the crown so as to set up a tension in the hatband, and the prongs 26, 27 are pressed into the hat body,

the central loop 28 remaining between the bow and the plain end 15, of the hatband, and acts as a stop to prevent the prongs 26, 27 from loosening their hold on the crown.

5 To remove the hatband, the bow end is gripped and turned away from the hat until the prongs 26, 27 disengage from the hat body. The hook member 16, may then be disengaged.

It is thus readily seen that there have been 10 provided simple, inexpensive fastening devices for quickly attaching to or detaching hat bands from straw or felt hats, or for similar devices where a dependable fastening means is desired for ribbonlike bands which 15 must be placed in assembled relation by inexperienced persons.

Having thus described my invention, I claim as new and desire to secure by Letters Patent:—

20 1. In detachable fastening devices for hat bands, means for attaching the bow end of the band, said means comprising hinged prongs and a loop portion intermediate the prongs rotatable as a unit relative to the hinge body, said hinge device positioned within the bow end of the hat band and the prongs and loop piercing the hat band fabric and positioned longitudinally of the said hat band

25 2. In a detachable fastening device for hat bands comprising a hinge body, a member carrying hinged prongs rotatable as a unit relative to said hinge body, said hinge body positioned within the boy end of a hat band, and the hinged prongs piercing the hat band 30 fabric and adapted to engage the crown of a hat and means attached to said member carrying said prongs to force the prongs flatwise when the prongs pierce the crown.

35 3. In a detachable fastening device for hat bands comprising a hinge body, hinged prongs and a member substantially on the same plane and intermediate said prongs and rotatable as a unit relative to the hinge body, said hinge body positioned within the bow 40 end of a hat band, and the prongs and intermediate member piercing the hat band, said prongs being adapted to pierce the crown of a hat and when forced flatwise the crown is held between the said prongs and intermediate 45 member.

50 Signed at Plainfield, in the county of Union and State of New Jersey, this 1st day of November, A. D. 1929.

FREDERICK JOHN CHEMIDLIN.
